CLOTHES PROP HOLDER

Archie N. Sinclair and John Reilly, Toledo, Ohio

Application April 29, 1938, Serial No. 205,038

4 Claims. (Cl. 248—353)

This invention relates to clothes line prop attachments and is more particularly directed to a device of this character which may be secured to the upper end of a clothes line prop to grip and hold a clothes line in proper position with respect to the prop.

An object of the invention is to provide means for engaging or disengaging the prop and the line without skill on the part of the user.

Another object of the invention is to provide a device of this character having a multiplicity of line gripping means for the convenience of the user.

A further object of the invention is to provide a device of the kind indicated, which is substantially but simple in construction, economical, to manufacture, and particularly efficient and practical in use.

Further objects and advantages will appear from a study of the following detailed description taken in connection with the accompanying drawing, in which:

Figure 1 is a side view of a form of the invention as applied to a prop;

Figure 2 is an end view of the device shown in Figure 1;

Figure 3 is a vertical sectional view through one of the line engaging loops; and

Figure 4 is perspective view showing the interior of the fastening plate.

Referring to the drawing, 10 indicates a portion of a clothes line prop or staff which may be of any suitable length. The prop 10 is illustrated as being made of wood, but it will be understood that other suitable material may be used, as for example, metal or metal alloy, either of solid or tubular cross section.

At the upper end of prop 10 and embracing two opposite edges thereof, are a pair of clips or plates 12 of like construction and therefore interchangeable. Plates 12 are preferably of channel form having side flanges 13 engageable with the sides of the prop 10. The plates are perforated as at 14 to receive screws 15 or other suitable means for affixing the plates to the prop.

Thus a prop engaging portion is provided, upwardly and inwardly from which extends a spring receiving portion 16, flanged as at 17. A pair of integral, spaced tongues 18 project from opposite portions of the flange 17.

When the plates 12 are assembled upon the prop in opposed relation, portions 16 converge slightly and suspend therebetween a spring 20, preferably of the helically coiled expansion type. The spring ends are secured in portions 16 by means of the tongues 18 bent inwardly and around the end convolutions 21 of the spring. Spring 20 is compressed between the plate ends

and due to the angularity of plate portions 16 the upper portions of the convolutions are compressed to a slightly greater degree than are the lower portions. Otherwise, the spring 20 is disposed generally horizontally and substantially parallel to the end of the prop 10.

The lower portions of the convolutions are spaced in comparatively close relation and provide sufficient resilient force to firmly grip and hold the clothes line, and particularly against undesirable lateral displacement. The more closely spaced upper portions of the convolutions serve to prevent abnormal vertical displacement or disengagement from the clothes line. As more particularly illustrated in Figure 3, the adjacent convolutions or line gripping loop distorts the clothes line to further enhance engagement therewith.

Due to the multiplicity of convolutions and therefore line engaging loops, it will be clear that the clothes line may be engaged between any of the loops, it being unnecessary for the user to attempt to engage the line with a particular portion of the spring.

What we claim is:

1. In combination with a clothes line prop, a pair of inwardly flanged plates embracing opposite edges of said prop, said plates having portions projecting upwardly and inwardly beyond the end of said prop and adapted to receive a spring element, a coiled spring interposed between said plate portions, the adjacent convolutions of said spring being adapted to receive and grip a clothes line, and tongues integral with said plate portions for securely retaining said spring in line receiving position.

2. In combination with a prop, a pair of flanged plates secured to one end of said prop, said plates being provided with spring receiving portions disposed above the end of the prop, and a spring interposed between said spring receiving portions and having its ends interlocked with said portions, said spring providing a plurality of loops for engaging a clothes line.

3. A clothes line holder comprising a prop, a pair of spaced plates having inwardly converging end portions at one end of said prop, and a spirally coiled spring interposed between said end portions adapted to grip a clothes line between two adjacent convolutions of said spring.

4. A clothes line holder comprising a prop, a pair of oppositely disposed flanged members secured to said prop, and a generally horizontally disposed spring interposed between said members and tensioned thereby to provide adjacent loops to grippingly engage a clothes line.

ARCHIE N. SINCLAIR.
JOHN REILLY.
